UNITED STATES PATENT OFFICE

ADALBERTO GARELLI, OF MILAN, ITALY

STARTING DEVICE FOR INTERNAL COMBUSTION ENGINES

Application filed July 16, 1931, Serial No. 551,260, and in Italy July 19, 1930.

This invention relates to apparatus for starting internal combustion engines and has for its object an arrangement of this type in which a transmission element interposed between the crank shaft and secondary shafts (cam shaft and magneto shaft, etc.) is used to give the starting impulse.

With this arrangement the starting is effected without addition of other parts to the motor and consequently without increasing its weight or size and with a high ratio of transmission without introducing another gear between the starting element and the motor shaft.

According to this invention the idler gear of the timing gear train of the engine between the engine shaft and the secondary shafts is adapted to be operated through a ratchet or one-way clutch by a starting crank and said gear may be mounted on a spindle operated by the starting crank and one-way clutch connected therewith, or it may be solid with a shaft, as a distribution shaft.

The arrangement of this invention is also adapted for starting an engine by remote-control means, the starting impulse being produced on a flexible member which is wound on and attached to a rotatable member connected with said pinion by the intermediate of a one-way clutch or coupling.

Embodiments of the present invention are illustrated by way of example on the annexed drawing in which

Figure 1 is a front view of a two-stroke single-cylinder engine provided with an embodiment of this invention;

Figure 2 is a section of the same on line 2-2 of Fig. 1;

Figure 3 is a front view of a construction embodying a cord and drum starting device and

Figure 4 is a section on line 4-4 of Figure 3.

In the embodiment of Figures 1 and 2, a starting crank 1 is solid with a spindle 2 loose in a bearing 3 provided in the engine casing 4. The engine which is assumed by way of example to be a two-stroke single-cylinder one comprises a crank shaft 5 driven by a piston and

connecting rod (not shown) and journaled in bearings 6 and 7 of casing 4. Said crank shaft 5 has a flywheel 8 outside of said casing 4 and it carries a pinion 9 solid therewith and driving the engine distribution and engine service-devices through an idler gear 10 and a pinion 11 solid with a part to be driven, an ignition magneto 12 being shown on the drawing as an example of such driven parts. Said idler gear 10 is mounted on the starting crank spindle 2 by means of an antifriction bearing 13 and is one-way connected therewith by means of a ratchet or one-way clutch exemplified as comprising ratchet teeth 14 on spindle 2 and rollers 15 located intermediate said ratchet teeth 14 and the bore of the hub of gear 10.

At the time the engine is started the drive of starting crank 1 and spindle 2 is imparted by ratchet clutch 14-15 to the pinion 10 which drives pinion 9 and crank shaft 5 for starting purposes while during the normal engine operation the gear 10 revolves freely on spindle 2 to drive pinion 11 and parts associated therewith.

In the construction shown in Figures 3 and 4, the spindle 2 is provided with a driving drum or pulley 16 on which a rope or cord 17 is wound and attached by one of its ends, and then for starting the engine a pull is exerted on said cord 17 to drive drum 16, spindle 2 and gear 10 and impart a starting impulse to the engine crank shaft 5.

Conveniently the drum 16 is connected with a stationary part as the engine casing 4 by means of a return spring 18 which operates to wind up again the cord 17 on said drum 16 after operation, to make it ready for a subsequent starting operation.

Of course, any resilient return member may be used, as a resilient cord which winds on a drum connected with the said pulley or starting spindle.

Of course, said cord 17 may be operated by a remote actuation by leading it at any preferred location it being caused to run for such a purpose over loose pulleys not shown.

The arrangement of this invention is of large advantage particularly in connection with small engines in which a speed multi-

plying ratio is required intermediate the starting member, as a starting crank or pedal, and the engine shaft, such increased ratio being secured by pinions 10 and 9 without necessity for a separate member as the usual starting quadrant and ratchet pinion.

Further in the arrangement of this invention the end of the crank shaft 5 may be enclosed within the engine casing 4 or be availed of for other purposes than engine starting.

What I claim as my invention and desire to secure by United States Letters Patent is:—

1. In an internal combustion engine having a toothed wheel gear train for imparting rotation to secondary shafts of the engine during its operation, said gear train comprising an idler gear; a starting device comprising a starting operating member and means for connecting in a single direction of revolution said member with said idler gear of said gear train.

2. In an internal combustion engine having a toothed wheel gear train for imparting rotation to secondary shafts of the engine during its operation, said gear train comprising an idler gear meshing with a pinion of the engine shaft with a transmission ratio higher than 1:1; a starting device comprising a starting operating member and means for connecting in a single direction of revolution said member with said idler gear of said gear train.

3. In an internal combustion engine having a toothed wheel gear train for imparting rotation to secondary shafts of the engine during its operation, said gear train comprising an idler gear; a spindle, a starting operating member solid with said spindle, said idler gear being mounted for rotation on said spindle and a one-way clutch operative between said spindle and said idler gear.

4. In an internal combustion engine, a toothed wheel gear train between the engine shaft and secondary shafts of the engine, said gear train comprising an idler gear having a diameter greater than the diameter of a pinion solid with the engine shaft; a spindle, a starting operating member solid with said spindle, said idler gear being mounted for rotation on said spindle and a one-way clutch operative between said spindle and said idler gear.

5. In an internal combustion engine having a toothed wheel gear train for imparting rotation to secondary shafts of the engine during its operation, said gear train comprising an idler gear; a starting operating drum, a flexible member mounted on said drum for revolving the drum, a resilient return member for said drum, and a one-way clutch for connecting said drum with said idler gear of said gear train for transmission of the rotation of the drum produced by the actuation on the flexible member to the idler gear.

6. In an internal combustion engine having a toothed wheel gear train for imparting rotation to secondary shafts of the engine during its operation, said gear train comprising an idler gear; a spindle, a starting operating drum solid with said spindle, a flexible member mounted on said drum for revolving the drum, a resilient return member for said drum, said idler gear being mounted for rotation on said spindle, and a one-way clutch for connecting said spindle with said idler gear of said gear train for transmitting the rotation of the drum produced by the actuation on the flexible member to said idler gear.

In testimony whereof I affix my signature.

ADALBERTO GARELLI.
